DESIGN FOR A DECORATIVE NAIL

Benjamin Salzberg, New York, N. Y.

Application October 14, 1937, Serial No. 72,166

Term of patent 3½ years

To all whom it may concern:

Be it known that I, Benjamin Salzberg, a citizen of the United States, residing in the city of New York, in the county of New York and State of New York, have invented a new, original, and ornamental Design for a Decorative Nail, of which the following is a specification, reference being had to the accompanying drawing, constituting a part thereof.

Fig. 1 is a top elevational view of the decorative nail showing my new design, and

Fig. 2 is a side elevational view of the decorative nail shown in Fig. 1.

I claim:

The ornamental design for a decorative nail, substantially as shown.

BENJAMIN SALZBERG.
